(Cl. D58—6)

To all whom it may concern:

Be it known, that we, John D. Buckingham and Peter Fink, citizens of the United States, residing at Chicago, in the county of Cook and State of Illinois, have invented a new, original and ornamental Design for a Decanter or Similar Article, of which the following is a specification, reference being had to the accompanying drawing forming a part thereof:

Figure 1 is a perspective view of a decanter or similar article embodying our new design;

Figure 2 is a front elevational view of the decanter or similar article shown in Figure 1;

Figure 3 is a side elevational view of the decanter or similar article shown in Figure 1; and

Figure 4 is a plan view showing the decanter or similar article from the top.

We claim:

The ornamental design for a decanter or similar article, as shown.

JOHN D. BUCKINGHAM.
PETER FINK.
